UNITED STATES PATENT OFFICE.

CHARLES L. GOEHRING AND WILLIAM TROCHE, OF AKRON, OHIO; SAID
TROCHE ASSIGNOR TO SAID GOEHRING.

MACHINE FOR GRINDING CURVED WORK.

SPECIFICATION forming part of Letters Patent No. 737,396, dated August 25, 1903.

Application filed July 24, 1902. Serial No. 116,805. (No model.)

To all whom it may concern:

Be it known that we, CHARLES L. GOEHRING and WILLIAM TROCHE, citizens of the United States, residing at Akron, in the county of 5 Summit, State of Ohio, have invented certain new and useful Improvements in Machines for Grinding Curved Work; and we do hereby declare the following to be a full, clear, and exact description of the same, reference being 10 had to the accompanying drawings, forming a part of this specification, and to the letters of reference marked thereon.

This invention relates to improvements in apparatus designed for beveling plates, especially glass and equivalent material, and more particularly elliptical, round, or curved plates, the objects of the invention being to provide an apparatus which will be, as far as practicable, automatic in action, rapid, and capable 20 of grinding a true bevel of definite and uniform width on an elliptical or oval plate.

The invention consists, primarily, in an apparatus for grinding ellipses or irregular curves in which the cutting-surface on the 25 grinder is caused to maintain a definite and uniform relation to the shifting center of the work and regardless of the shifting of the cutting-surface due to the shifting of said center and thickness of the grinder.

30 The invention further consists in certain novel details of construction and combinations and arrangements of parts, all as will be now described, and pointed out particularly in the appended claims.

35 Referring to the accompanying drawings, Figure 1 is a side elevation of an apparatus embodying the present invention and designed for beveling elliptical or round plates. Fig. 2 is a view looking at the opposite side 40 of the machine. Fig. 3 is a front elevation with the work-holder removed. Fig. 4 is a top plan view. Fig. 5 is a view of the gearing for moving the grinder and rotating the work in grinding ellipses or irregular shapes.

45 Fig. 6 is a top plan view of the slide and adjustable eccentric for the work-holder. Figs. 7 and 8 are top and edge views of the adjustable eccentric alone. Figs. 9 and 10 are top and side views of the rotary head. Figs. 11 50 and 12 are top and side views of the slide.

Similar letters of reference in the several figures indicate the same parts.

The main frame of the machine, lettered A in the accompanying drawings, is preferably of metal and of suitable shape to support the 55 working mechanism of the whole apparatus. At the bottom it is preferably provided with an extended base A' and on the rear side near the top with a rearwardly-extending bracket A² for supporting the bearings of the grinder 60 or stone frame, as will be presently described. At the front the main frame is provided with vertically-extending ways or guides A³, adapted for coöperation with a vertically-movable bracket B, which constitutes the base of the 65 work-support and is moved vertically by means of a screw C, held in bearings on the main frame and adapted to be rotated by hand or power, as will be presently explained.

The bracket D, in which the frame E for the 70 grinder is directly pivoted, is adjustably mounted on the bracket A² and is adapted to be adjusted horizontally by the screw d and hand-wheel d', as is usual in this class of machinery. The said frame E is mounted to 75 swing on a transverse shaft E', journaled in the bracket D, and has fast and loose pulleys E² thereon, to which the driving power is applied. The grinder or stone F is mounted rigidly on a shaft F', carried in bearings Q, 80 movably supported at the forward end of the frame E, and is adapted to be rotated by a driving-gear, preferably consisting of a pair of sprocket-wheels f e and mounted, respectively, on the shafts E' and F' and having a 85 sprocket-chain connecting them, as shown in Figs. 1 and 2. To limit the downward movement of the frame E and stone, a limiting-bracket G extends upwardly from the frame A, and upon this limiting-bracket a set-screw 90 G' on the frame E is adapted to rest. Thus by adjusting the said set-screw G' the downward limit of movement of the stone may be engaged with the greatest accuracy. In operation it is designed that the stone shall occupy 95 a fixed position vertically, or, in other words, it does not ride on the work being done, but is held against vertical movement and the work is fed to the stone, and in order that the stone may be elevated to facilitate the 100

application of the work or the changing of the position of the work the frame E is provided with a downwardly-extending vertically-adjustable bracket G², on the end or 5 straight surface of which a roller or pair of rollers g, carried in the ends of crank-arms g', is or are adapted to work. Said crank-arms g' are mounted on a transverse shaft or center g², journaled on a bracket g³ of the 10 main frame, and they are adapted to be turned to raise the stone and frame E, first, by means of a counterweight H⁹, pivotally supported on the base of the machine and connected to one of the crank-arms by a link h, and, sec- 15 ondly, by means of a link H', extending downwardly and connected at its lower end with a handle H², projecting at the front of the machine in convenient reach of the attendant. The attendant may thus by depressing or 20 raising the handle raise or lower the stone, and the arrangement is preferably such that when the stone is depressed until the adjustable stop G' rests on the bracket G it will be locked in that position. This result is at- 25 tained by providing a second crank-arm H³ for operation by the handle H², which second crank-arm extends vertically and is provided at its upper end with a roller H⁴, adapted to take over a cam or curved surface H⁵ on the 30 bracket G². Thus when the outer end of the handle H² is depressed and its inner end raised the first effect is to move the roller H⁴ away from over the bracket G² and then to 35 elevate the frame E through the medium of the roller g, which contacts with the bottom face of the bracket G². In lowering the stone to working position again the roller H⁴ is moved back over the top of the bracket G² and locks the stone firmly in its adjusted po- 40 sition. The vertical adjustment of the bracket G² is effected by means of a screw H⁶. As before stated, the work is carried by the bracket B, which is vertically adjustable on the main frame, and in order to provide for 45 an angular adjustment the upper portion B' of the bracket is pivotally mounted in bearings b, held in adjusted position by a segment b', Fig. 1. Extending up through the bracket B' is a rotary head B², having a vertical axis 50 and adapted to be rotated by a shaft H, sup- ported in suitable bearings and having an axis coincident with the axis on which the bracket B' pivots, the connection between the shaft H and rotary head B² being formed by 55 miter-gears h. Thus said head may be rotated with the bracket in any desired angular adjustment.

On the bracket B' is an adjustable eccentric B³, Figs. 7 and 8, preferably guided in 60 right lines toward and from the grinder by being mounted in ways b³, the adjusting being effected by a screw b⁴. The rotary head B² passes through a slot in the eccentric and in its upper face is provided with slideways b⁵, adapted for the reception of a slide B⁵, having a central stud b⁶, on which the sup- 65 port B⁶ for the work is mounted. The slide

B⁵ is provided with downwardly-extending projections B⁷, embracing the eccentric. Thus as the head is rotated the slide and work will also be rotated and also moved toward and away from the grinder twice during each revolution. The adjustment of the eccentric determines the length of the ellipse or oval, and if it be adjusted to a concentric position the work will be rotated on a fixed center and the stone will grind a round instead of an ellipse or oval. The work is preferably fed positively to the grinder or stone by elevating the bracket B, which carries the entire work-support, and two mechanisms are provided for effecting this motion, the first being controlled by hand, so as to bring the work to its starting position, and the second being controlled automatically to advance the work with a relatively fast movement during the initial grinding and with a gradually-decreasing speed as the point is approached where the grinding operation should cease, and finally said feeding motion is automatically arrested entirely at the proper point, which may be predetermined by the adjustment of the mechanism and the depth of bevel desired. The feed is controlled through the screw C, and the mechanism for 95 driving this screw consists of a bevel-gear C' on the lower end of the screw, a corresponding bevel-gear C², mounted on a transverse shaft C³, but through which said shaft C³ may be moved longitudinally. The shaft C³ carries at one end a hand-wheel C⁴, by means of which the shaft may be rotated to adjust the work by hand. At the opposite end of said shaft there is journaled a worm-wheel K, adapted to mesh with a worm K', carried by the shaft K², having at its rear end a friction-disk K³. The connection between the worm-wheel K and shaft C³ is effected through the medium of a clutch C⁵, one section of which is connected with the worm-wheel K and the other section of which is mounted on the shaft C³, and the latter is movable longitudinally by means of a shifting-lever C⁶ to throw said clutch-sections into or out of engagement. At the rear of the machine 115 a secondary drive-shaft L is journaled in suitable bearings and driven by means of a pulley l, connected by a belt l' or otherwise with the main drive-shaft E', and upon this secondary drive-shaft L there is mounted a 120 friction-wheel L', which is keyed to said wheel, so as to be capable of a movement longitudinally thereof, but is rotated in unison with said shaft and is adapted to contact with the face of the friction-disk K³. With such 125 an arrangement it is obvious that if the friction-wheel L' be located centrally of the friction-disk K³ said disk will not be rotated or driven thereby and if said friction-wheel L' be moved gradually from its central position 130 toward the periphery of the friction-disk K³ said disk will be driven with a gradually-decreasing speed—that is to say, when the friction-wheel has in moving away from its cen-

tral position reached a point where it will drive said disk the disk will be given a comparatively rapid rotation; but as the path of travel of the friction-wheel becomes greater and greater the speed of rotation of the friction-disk is correspondingly reduced, but with a corresponding increase in the driving power of the wheel and disk.

The movement of the friction-wheel across the face of the disk gives the desired differential feed, and for moving the said wheel various forms of mechanism may be employed—for instance, either the first or second mechanisms described in the contemporaneous application, Serial No. 48,342, series of 1900; but in the present application only the second mechanism referred to is illustrated, as it will be claimed specifically herein.

By reference to the drawings it will be seen that the friction-wheel L' is controlled by a lever-arm M , pivoted at the upper end in a bearing M' , and this arm is shifted through the medium of a link O , which at one end is pivotally and preferably adjustably connected with the lever-arm and at the opposite end adjustably connected with a crank O' . Upon the crank a scale for indicating the adjustment is preferably provided. The crank O' is carried by a shaft O^2 , suitably journaled in bearings O^3 , attached to the main frame, and at its forward end provided with a bevel gear-wheel O^4 , adapted to mesh with a corresponding gear-wheel O^5 , mounted on the end of the shaft C^3 , but held against longitudinal movement therewith by a clip or collar O^6 . The shaft C^3 , being the shaft through which the work-support is elevated, imparts a motion to the crank O' exactly proportioned to the elevation of the work-support, and said crank O' through the link O moves the friction-wheel correspondingly and gives the desired differential rate of feed to the work-support, whereby during the initial grinding or when a rough cut may be made and the material of the work removed very rapidly because of the narrowness of the edge, causing said work-support to move upward quickly, and as the width of the cut increases and it becomes desirable to make a more finished surface the work is fed much slower until as the point of completion is reached the feed is automatically arrested by a mechanism to be now described. While the feed may be arrested by shifting the driving-gear at a number of different points, it is found most convenient to do this work by simply separating the friction-wheel and friction-disk, as in the aforesaid application. For this purpose the friction-disk and its shaft are preferably mounted to have a slight longitudinal movement, and they are adapted to be held up to their work by a flat spring P , Fig. 1, working between the collars p' on the shaft K^2 , which carries the friction-disk. Thus when said spring is under tension the disk will be held forward against the friction-wheel L' ; but if the tension of the spring is relieved the

disk and wheel will be separated slightly or the pressure between them be sufficiently relieved to arrest the further feed of the work-support. The spring is put under tension by means of a gate P^3 , pivoted to the main frame and having a set-screw P^4 adapted to bear on the upper end of the spring P , said gate being held forward with the set-screw in contact with the spring by means of a knocker or dog P^5 , which is thrown into position by a spring whenever said gate is swung forwardly, so as to put the spring under tension. The gate is swung forward to put the spring under tension by means of a collar P' , contacting with an arm P^2 on the gate, and said collar P' is mounted on the shaft C^3 and preferably on one of the sections of the clutch C^5 , whereby whenever said shaft is moved longitudinally it will put the sections of the clutch into engagement, the gate will be swung forward, the spring put under tension, and the friction-wheel and disk brought together and held by the dog or knocker P^5 until said dog or knocker is released.

In the ordinary operation of the machine the shaft C^3 makes but a partial rotation to feed the work, and hence it is a simple matter to provide a projection on said shaft which at the proper instant will contact with the dog or knocker and release the gate, so as to arrest the feed. It will be seen that we have provided the shaft C^3 with an adjustable collar P^7 , having a projection P^8 on one side thereof which is adapted to contact with the front end of the dog or knocker, so as to release the gate. This collar P^7 may be set at any desired angle with relation to the shaft C^3 and secured by a set-screw p^7 to arrest the feed when the desired depth of cut or bevel has been made. As thus far described if power were supplied for rotating the shaft H^9 the apparatus would operate to grind ellipses or ovals; but owing to the fact that the center of the work in irregular work of this kind is a shifting center and to the further fact that the grinder must have an appreciable thickness the surface of the grinder on one side or the other of the center will become active and work into or cut away the ellipse at the four parts intermediate the major and minor axes. In beveling this results in a bevel of irregular width and narrowest at the major and minor axes. The present apparatus is designed to overcome this difficulty by a compensating movement of the work and grinder with relation to each other, whereby all portions of the grinder-face will cut uniformly and form an accurate ellipse or bevel. As the most convenient and universally-adaptable means for accomplishing the desired end the grinder is given a bodily movement toward and from the work, such movement being timed to accord with the rotation of the work and adjusted to the proportions of the ellipse, oval, or other figure being operated upon. As before stated, the bearings Q , in which the grinder is journaled, are mov-

ably mounted on the frame E, being preferably guided on suitable ways thereon, and each bearing is connected by a connecting-rod Q' with an adjustable crank q. These 5 cranks are preferably formed by mounting pins adjustably in transversely-slotted disks q, carried on opposite ends of a transverse shaft Q². The shaft Q² is rotated by gears R R' from the drive-shaft E'. The rotary head 10 receives its motion from the shaft H', and the latter in turn receives its motion from the main drive-shaft E' through the medium of a telescoping diagonal shaft S and bevel-gears S' and S², the shaft and gears being held in 15 alinement and the gears in mesh by swivel-bearings S³, adapted to permit the adjustment or feed movements of the work-support or frame E without interference. Obviously the necessary movement is a relative movement 20 of the rotary head and grinder, and hence instead of moving the grinder bodily the rotary head might be given a bodily movement toward and from the grinder—as, for instance, by mounting the shaft H, rotary head, and 25 parts co-operating therewith on a slide receiving motion from an adjustable cam or crank and operating in proper relation to the rotation of the head. By adjusting the throw of the cranks q the extent of bodily movement 30 of the stone may be regulated to grind ellipses of any desired proportions, and by varying the speed of rotation of the head and movement of the stone other irregular shapes may be ground with equal facility.

35 Having thus described our invention, what we claim as new, and desire to secure by Letters Patent, is—

1. In a grinding-machine for curved work 40 the combination of the following instrumentalities, to wit: a rotary grinder, a rotary head, driving mechanism for simultaneously rotating and moving said grinder and head toward and from each other, a work-support mounted on said head to rotate in unison therewith and movable independently thereof toward 45 and from the grinder and an eccentric for moving the support independently; substantially as described.

2. In a beveling-machine for curved work 50 the combination of the following instrumentalities, to wit: a rotary grinder, movable transversely of its axis of rotation, a rotary head, driving mechanism for simultaneously rotating said head and periodically moving 55 the grinder transversely of its axis and a work-support mounted on said head to rotate in unison therewith; substantially as described.

3. In a beveling-machine, the combination 60 of the following instrumentalities, to wit: a rotary grinder, bearings in which the grinder is journaled movable in a plane at right angles to the axis of rotation, a drive-shaft, driving connections between said shaft and bearings in which the grinder is journaled 65 for periodically moving the grinder bodily transversely of its axis during the grinding operation, a rotary support for the work pre-

sented to the grinder and driving mechanism for rotating said support; substantially as described.

4. In a beveling-machine, the combination 70 with a rotary grinder, a pivoted grinder-frame and bearings in which the grinder is mounted movably supported in said frame whereby the grinder may be given a bodily movement independent of the frame, of a driving-gear connected with said bearings for giving the grinder a periodic bodily movement, a rotary support for the work presented to the grinder and driving connections between the work-support and driving mechanism for moving the grinder; substantially as described.

5. In a beveling-machine, the combination 80 with a rotary grinder, a pivoted grinder-frame, bearings in which the grinder is mounted movable toward and from the axis of the frame, of a drive-shaft, gearing intermediate the shaft and grinder for rotating the latter, gearing intermediate the shaft and bearings 90 for moving the grinder toward and from the axis of the frame, a rotary work-support and gearing intermediate said work-support and shaft for rotating the support; substantially as described.

6. In a beveling-machine, the combination 95 with a rotary work-support and driving-gear for rotating said support, of a rotary grinder movable bodily toward and from the support, an adjustable crank for moving said 100 grinder bodily and gearing for moving said crank timed to move said crank in unison with the rotation of the work-support; substantially as described.

7. In a beveling-machine, the combination 105 with the rotary work-support and gearing for rotating the same, of a pivoted frame a grinder journaled in bearings movable on said frame, an adjustable crank for moving said bearings, and a driving-gearing for moving said bearings in a predetermined ratio to the rotation 110 of the work-support; substantially as described.

8. In a beveling-machine, the combination 115 with a rotary work-support, a driving mechanism for rotating the same and means for moving the support vertically, of a bodily-movable rotary grinder, a driving mechanism for moving the grinder bodily at predetermined intervals and a driving mechanism 120 for rotating the grinder; substantially as described.

9. In a beveling-machine, the combination 125 with a rotary grinder, a vertically-movable rotary work-support and means for moving said support vertically, of a driving-gear for rotating said support embodying a telescoping shaft whereby the same may accommodate itself to the vertical adjustment of the support; substantially as described.

10. In a beveling-machine, the combination 130 with a rotary grinder, vertically-movable work-support and a driving mechanism for moving said work-support vertically embody-

ing a friction-disk and a friction-wheel movable transversely of said friction-disk, of a shifting mechanism for said friction-wheel embodying a shifting arm and a crank connected therewith and controlled in its angular position by the vertical position of the work-support; substantially as described.

11. In a beveling-machine, the combination with a rotary grinder, vertically-movable work-support, and a driving mechanism for moving said work-support vertically embodying a friction-disk and a friction-wheel movable transversely of said friction-disk, of a shifting mechanism for said friction-wheel embodying a shifting arm and an adjustable crank connected therewith and controlled in its angular position by the vertical position of the work-support; substantially as described.

12. In a beveling-machine, the combination with a rotary grinder, vertically-movable work-support and a driving mechanism for moving said work-support vertically embodying a vertical screw, a transverse shaft geared thereto, a friction-disk for rotating the shaft and a movable friction-wheel for rotating the disk, of a shifting mechanism for said friction-wheel embodying a shifting arm, an adjustable crank and a driving connection between said crank and the transverse shaft, whereby the position of the friction-wheel is determined by the position of the shaft and work-support; substantially as described.
